CLAIM

The ornamental design for a cookware vessel, as shown and described.

DESCRIPTION

FIG. 1 is a top isometric view of a cookware vessel showing the design;

FIG. 2 is a bottom isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The dashed lines shown in the drawings illustrate portions of the cookware vessel that form no part of the claimed design.

1 Claim, 8 Drawing Sheets
